UNITED STATES PATENT OFFICE.

HENRY LEA, OF ST. HELENS, ENGLAND.

WIRE CLIP.

1,079,989.

Specification of Letters Patent.

Patented Dec. 2, 1913.

Application filed July 10, 1911. Serial No. 637,701.

To all whom it may concern:

Be it known that I, HENRY LEA, a subject of His Majesty the King of Great Britain and Ireland, residing at 1 Hayes street, 5 St. Helens, in the county of Lancaster, England, have invented a new or Improved Wire Clip, of which the following is a specification.

This invention consists in features of construction and combinations relating to devices hereinafter described and more particularly set forth in the claims.

In order that my invention may be readily understood and carried into practice, reference is hereby made to the accompanying sheet of drawings wherein like letters of reference indicate corresponding parts wherever occurring throughout all the figures.

Figure 1 is a perspective view of a wire 20 clip which is intended for use chiefly but not exclusively in connection with framed blackboards. Fig. 2 is a perspective view of a modification of the forementioned device, as to the length and shape of the sides of the 25 front jaw, which is intended for use chiefly but not exclusively in connection with unframed blackboards, map-easels, and the like. Fig. 3 shows the first-named device engaged to a framed blackboard and utilized as both 30 a clip and hook.

In accordance with my invention I bend a metal wire of suitable degrees of flexibility and rigidity or strength in the form as shown in the accompanying sheet of drawings and hereinafter more particularly described. The wire is doubled upon itself at its center to form a tongue *b* of which that portion other than the tip *c* is inclined upwardly and forwardly; the tip *c* is bent 35 rearwardly and, when the device is attached to a blackboard or similar furniture, as shown in Fig. 3, projects slightly above the edge thereof. The two parts of the wire then pass oppositely horizontally to form a back jaw, whence they are bent upwardly and rearwardly, and then directly forwardly to form spacing members or bridges which lie in a horizontal plane. The ends are then bent downwardly and rearwardly for a short 40 distance, and then bent, as at *d*, further rearwardly, and then inwardly horizontally toward each other to form the members *e* of the front jaw. They then extend a slight 45 distance forwardly and toward each other,

forming the portions *f*, of which the extremities *a* are interlocked and, preferably, further secured by soldering.

In the modification shown in Fig. 2, the bend *d* is dispensed with, and the downwardly extending sides of the front jaw are slightly shorter than are those of the back 60 jaw so that, in engaging the device, the back jaw may, initially, be placed sufficiently below the edge of the blackboard to provide a purchase to facilitate the front jaw 65 being pulled forwardly by means of the grip *a* formed by the interlocked ends, and thus effect ready engagement.

The device is clipped over the edge of the blackboard; but, of course, it will be understood that to secure effective engagement it may be necessary in some cases preliminarily to press the front and back jaws nearer to or farther apart from each other so as thereby to increase or lessen, respectively, the 70 clipping force of the device.

It will be seen that of the tongue *b* that part other than the tip *c* is bent upwardly and forwardly; and thereby I provide a means of adding to the clipping force of the 80 back jaw. Of this tongue the tip *c*, which, when the device is engaged to a blackboard, projects slightly beyond the edge of the board, is bent rearwardly; by which means I provide a hook from which sheets having 85 hanging cords may be hung, as illustrated in Fig. 3.

Respecting the device shown in Fig. 1; it should be observed that the sides of the front jaw are bent farther rearwardly at *d* 90 so that when the device is engaged to a framed blackboard, as shown in Fig. 3, the parts *e* of the front jaw press against the surface of the board and thus form the clip.

Respecting more particularly the device 95 illustrated in Figs. 1 and 3, the two portions *f* are bent forwardly to meet at *a* so that when the device is engaged to a framed blackboard there is inclosed by the said two parts, together with the surface of the board, 100 a sufficient space *g*, somewhat triangular in shape, through which to allow the hanging cord of a sheet to be passed upwardly prior to its being placed over the hook; whereby I provide a means of enabling the hanging 105 sheet to lie close to the surface of the board. The part *a* affords a convenient grip by which the front jaw is pulled from the face.

of the blackboard to permit the edge of a sheet to be passed under it, as shown in Fig. 3.

The sides of either jaw of the device may be flattened laterally and a name or other matter embossed thereon.

I claim:

1. A device of the class described, formed from a single piece of wire, comprising a horizontal portion, a forwardly and upwardly inclined tongue formed intermediate the ends of the horizontal portion, the end of the tongue being bent rearwardly, the ends of the horizontal portion being bent upwardly and inclined rearwardly, then bent forwardly to form spacing members, the ends then bent downwardly and rearwardly for a short distance and then bent farther rearwardly, then inwardly horizontally toward each other, then forwardly and

toward each other, the ends of the wire being interlocked.

2. A device of the class described, formed from a single piece of wire, comprising a horizontal portion, a forwardly and upwardly inclined tongue formed intermediate the ends of the horizontal portion, the end of the tongue being bent rearwardly, the ends of the horizontal portion being bent upwardly and inclined rearwardly, then bent forwardly to form spacing members, the ends then bent downwardly and rearwardly, then inwardly horizontally toward each other, then forwardly and toward each other, the ends of the wire being interlocked.

HENRY LEA.
